UNITED STATES PATENT OFFICE

ROBERT FRIEDRICH, OF PHILADELPHIA, PENNSYLVANIA

DESIGN FOR HOSIERY

Application filed November 20, 1928. Serial No. 28,954. Term of patent 7 years.

To all whom it may concern:

Be it known that I, ROBERT FRIEDRICH, a citizen of the United States, residing at Philadelphia, in the county of Philadelphia and State of Pennsylvania, have invented a new, original, and ornamental Design for Hosiery, of which the following is a specification, reference being had to the accompanying drawing, forming a part thereof.

The figure is a rear perspective view of a stocking showing my new design, a part of the stocking being broken away.

I claim:

The ornamental design for hosiery, as shown.

ROBERT FRIEDRICH.
